United States Patent Office.

JAMES C. FRENCH, OF MONMOUTH, ILLINOIS.

Letters Patent No. 87,923, dated March 16, 1869.

IMPROVEMENT IN CULTIVATORS.

The Schedule referred to in these Letters Patent and making part of the same.

To all whom it may concern:

Be it known that I, JAMES C. FRENCH, of Monmouth, in the county of Warren, and State of Illinois, have invented a new and useful Improvement in Cultivators; and I do hereby declare that the following is a full, clear, and exact description of the same, reference being had to the annexed drawings, making part of this specification, in which—

Figure 1 is a perspective view;

Figure 2 is a side elevation;

Figure 3 is a sectional elevation, showing the method of securing the plow-beams to the double-joint attachment *a*; and

Figure 4 is a detailed view of the joint-piece *a*, showing the manner of attaching it to the axle, the plow-beam, and to the upright, or standard, *O*.

Corresponding letters denote corresponding parts in the several figures.

The object of this invention is an improvement in cultivators, or cultivating-plows; and

It consists in the construction of the double joint, by which the plow-beams are attached to the axle and frame-work of the machine, and in the combination and arrangement of other parts, as will be hereinafter described.

A A are the wheels, which are of any form and size suitable for the purpose, and hence need not be further described here.

B is the axle, which is constructed in two sections, one for each wheel, and consists of the bearing-portion, upon which the wheel turns, and an arm, which is turned at a right angle, or nearly so, thereto, for the purpose of enabling it to be secured to the standard *O*; the above described construction being clearly shown in fig. 4 of the drawings.

O O are uprights, or standards, made of metal or any other suitable material, and are forked at their lower ends, to receive that portion of the joint-piece *a* which has vertical sides.

To the lower outer face of said standards, the arm of the axle *B* is secured, by bolts, which pass through said arm, and through the standard and joint-piece *a*.

That portion of the arm, or axle, which rests upon the standard *O*, is provided with a series of holes, to receive the bolts above described, which are arranged vertically therein, so that, by changing the bolts from one to the other of said holes, the standards may be raised or lowered, with reference to the axle of the carriage.

D D are the plow-beams, which are attached, at their forward ends, to horizontal portions of the joint-piece *a*, by having a bolt passed through both, upon which the beam swings freely, so that the rear end of the plow-beams, with the plows, has any desired amount of lateral motion, with reference to the line of motion of the carriage, and to the rows of the growing crop.

To the rear ends of these plow-beams, uprights *E E*

are secured, in the usual way, to the lower ends of which the plows, or teeth, are secured.

Handles *F* are also secured to said beams, to enable the operator to guide said plows, with reference to the rows of corn or other crops which he may be cultivating.

E E are the standards, attached to the plow-beams, and to the lower ends of which the plows are attached, as above described.

F F are the plow-handles.

G is a cross-beam of timber, say three by four inches, which rests in a recess formed upon the upper ends of the standards *O*, and upon a flange formed upon the inner sides of said standards, to which flanges the lever is bolted.

To this cross-beam the tongue *H* is secured.

H is the tongue, which is secured to the cross-beam, as above described, and to the lower ends of the standards *O*, by braces, as clearly shown in figs. 1 and 2 of the drawings.

The tongue extends rearward from the cross-beam *G*, for a distance sufficient to enable it to carry upon its end a strap, *I*, of iron, which is secured thereto, and which extends downward, say, ten or twelve inches, and has, upon its lower ends, hooks, formed to receive the braces *b* of the forward one of the series of plows *E*, so that when not in use, said plows may be raised up, and be secured in their raised position, by having said braces placed within said hooks.

I is the strap of iron, placed upon the end of the tongue, as and for the purpose above described.

a is the joint-piece, above alluded to, which consists of a piece of metal, with its front and rear portions formed at a right angle with each other, the rear portion being horizontal, to receive the end of the plow-beam, and the front portion having its sides vertical, to enter the slot in the lower end of the standards *O*, as clearly shown in fig. 4 of the drawings.

It will be seen, that the rear, or horizontal portion of this joint-piece has a series of holes bored in it, by which the front end of the plow may be carried nearer to or further from the wheels of the machine, as may be desired.

b b are braces, which extend from a suitable point on the plow-beams to a part upon the uprights just above where the plows are attached, and are for the purpose of strengthening said uprights.

Having thus described my invention,

What I claim, and desire to secure by Letters Patent, is—

1. The construction of the joint-piece *a*, as and for the purpose described.
2. In combination with said joint-piece, the plow-beam *D* and the upright standard *O*, substantially as shown and described.
3. The standard *O*, substantially as shown and described.

4. The combination and arrangement of the standard C, cross-beams G, and axles B B.
5. The arrangement of the plow-beams D D, with reference to the joint-piece a, by which said beams may be carried nearer to or further from the wheels of the machine.

In testimony whereof, I have signed my name to this specification, in the presence of two subscribing witnesses.

Witnesses: JAMES C. FRENCH.
JOSEPH MCLEAN,
GEORGE W. MCINTIRE.
